FRANK W. MILLER, OF CHICAGO, ILLINOIS.

BOILER WASHING AND FILLING SYSTEM.

1,357,717.

Specification of Letters Patent.

Patented Nov. 2, 1920.

Application filed May 7, 1917. Serial No. 167,057.

To all whom it may concern:

Be it known that I, FRANK W. MILLER, a citizen of the United States, residing at Chicago, in the county of Cook and State of Illinois, have invented certain new and useful Improvements in Boiler Washing and Filling Systems, of which the following is a specification.

This invention relates to boiler washing and filling systems by means of which locomotive boilers are blown off, washed out and refilled with hot water, and has for one of its primary objects the provision of a system of this character which will be extremely simple in construction and operation and which can be installed at a low cost.

Systems of this general character customarily have provisions for conserving both the blow-off steam and blow-off water, the steam being utilized for heating the fresh refilling water while the blow-off water is returned to the boiler either for washout or refilling purposes. In many localities, however, the conservation of the blow-off water is not of sufficient importance to justify the expense of installation and maintenance of a complicated and costly system. And furthermore, in some instances, because of the character of the water it is inadvisable to return the blow-off water to the boiler for any purpose whatsoever. One of the features of my present invention consists in providing a system which will conserve and utilize the blow-off steam while permitting the blow-off water to be discharged to the sewer, and in delivering water to the locomotive at suitable temperatures for both the washout and refilling purposes.

Another feature of my invention consists in using but one tank, which contains the water for both washout and refilling purposes, and in conducting this water to the boiler for both washout and refilling purposes through a single pipe line, thereby eliminating one of the tanks and one of the pipe lines which have heretofore been customarily considered necessary.

A further feature of my invention consists in maintaining the water in the tank at suitable temperature for washout purposes so that it can be used in washing out a locomotive boiler without being tempered, and also in the provision of means whereby the temperature of the water may be increased when it is being used for refilling purposes.

For the purpose of facilitating an under-

standing of my invention I have illustrated on the accompanying sheet of drawings, somewhat diagrammatically, one practical and preferred embodiment of the invention. 60 On the drawings—

Figure 1 illustrates in elevation one form of the invention; and

Fig. 2 is an enlarged detail view of the means whereby the water is further heated 65 for refilling purposes.

Referring to the drawings, reference character 5 indicates a single tank, of sufficient capacity to contain a supply of water for both washout and refilling purposes. Water is supplied to this tank from a city main or other suitable source of supply through a pipe 6 which is equipped with a nozzle 7 projecting through a cross fitting 8 into a delivery pipe 9 which extends downwardly 75 in the tank below the water level therein and is provided at its lower end with a drum or silent steam delivery device 11. A constant predetermined water level is maintained in the tank by means of a float mechanism comprising a float valve 12 interposed in the pipe 6 and controlled by a float 13 of well known construction attached to a pipe 14 which is connected directly with the tank 5, through the pump suction pipe 15 connected 80 at one end with the pump 16, and at its other end with the interior of the tank. 85

The steam blown off from a locomotive, indicated generally by reference character 16, through the blow-off drop 17 connected 90 to the dome of the locomotive or any other convenient position, is conducted through a blow-off pipe line 18 to the tank 5 through the fitting 8 and pipe 9, which also serves as an admission pipe for the water. Since 95 the steam and water are both admitted to the tank through the same pipe it will be manifest that when water is being admitted through the nozzle 7 an injector action will be set up, which, together with the partial 100 vacuum caused by a condensation of the steam when it comes in contact with the cold water, reduces the back pressure in the blow-off line and facilitates the blowing off operation.

Since the heat units of the blow-off steam will usually be insufficient to maintain the water in the tank at a proper temperature for washout purposes I have also connected to the fitting 8 an exhaust steam pipe 19, 110 which receives the exhaust steam from the engines of the power house, and this steam

is also admitted to the tank 5 through the pipe 9 in a similar manner to the blow-off steam supply from the blow-off line 18. In order to prevent the exhaust steam from backing up in the blow-off line 18 when no boiler is being blown off I have provided a check valve 21 and similarly, to prevent blow-off steam under high pressure from backing up in the exhaust steam line 19, I have provided this line with a check valve 22. The admission of the exhaust steam to the tank is automatically regulated by a thermostatically controlled valve 23 which is automatically opened and closed by a thermostatic element 24 projecting into the water in the tank. When the water is below the temperature desired for washout purposes exhaust steam is admitted, and when the maximum washout temperature has been reached the valve 23 is automatically closed, so that the water never becomes hotter than it can be handled by the washer. It will be manifest therefore that I have made provision for the maintenance of a supply of water which is always at the proper temperature for washing out a locomotive.

This water is conducted to the roundhouse for both washout and refilling purposes through a pipe line 25, the water being withdrawn from the tank through the suction pipe 15 into the pump 16 and delivered by the pump under pressure to the washout and refilling line 25. The pump is preferably steam-driven and receives the steam by which it is operated through a branch pipe 26 connected with a live steam supply pipe 27, which receives its steam from the power boilers or any other suitable source. The exhaust steam from the pump is delivered through the branch pipe 28 into the exhaust steam line 19, so that it also is delivered to the tank 5 to heat the water therein.

At each washout pit in the roundhouse the post 29 is provided with a drop 31 connected at its upper end with the washout and refilling line 25. The water from the tank is delivered to these drops through the pipe line 25, and when it is being used for washout purposes the flexible hose 32 is equipped with the usual washout nozzle by means of which the washer delivers the water into the different points of the boiler to thoroughly clean the same. The drop is provided with the usual hand valve 33 by means of which the water may be shut off or turned on as desired.

Since it is desirable to deliver the refilling water to the boiler at a much higher temperature than the washout water I have made provision for raising the temperature of the water at the drop so that it will be delivered to the boiler at as high a temperature as is practicable. With this end in view I have provided a live steam drop 34

connected at its upper end with the live steam supply pipe 27, and connected at its lower end with a branch fitting 35 interposed between the water drop 31 and the hose 32. This fitting is also equipped with an injector nozzle 37, preferably of twin construction, as shown in Fig. 2, so that when water is delivered from the drop 31 steam will be drawn in from the drop 34 by an injector action which thoroughly mingles the steam with the water and consequently materially increases the temperature of the water. The amount of steam admitted may be regulated by a hand valve 38 or, if preferred, an automatic thermostatically controlled valve might be substituted for this hand valve so as to relieve the attendant of the duty of turning on the requisite amount of steam. In order to prevent the steam from backing up in the water drop in the event the water pressure became unduly low and the steam pressure unduly high I have provided a check valve 39 interposed preferably between the nozzle 37 and the hand valve 33.

In the operation of my system the water in the locomotive is blown off directly into the pit, from whence it is discharged into the sewer and the blow-off steam is conducted to the tank 5 where it heats the water therein. This steam is also supplemented, as previously described, by exhaust steam from the power plant, the admission of which is automatically controlled so that the temperature of the water in the tank is always suitable for washout purposes. The water is withdrawn from the tank and delivered to the drops of the roundhouse at suitable temperature for washing out, and when the washing out operation has been completed the hose is fixedly connected to the boiler and the water is turned on to refill the boiler. When the refilling operation is begun the live steam is also turned on which, as it mixes with the water, materially raises its temperature so that when the boiler is filled steam may be quickly gotten up.

It will thus be manifest that I have provided a system which is extremely simple and which delivers uncontaminated water to the boiler through a single pipe line for both washout and refilling purposes, the washout water being always at the requisite temperature and the refilling water being raised in temperature to any desirable degree. The details of construction illustrated and described are, of course, capable of considerable modification and variation without departing from the scope of the invention as defined in the following claims.

I claim:

In a boiler washing and filling system, the combination of a tank adapted to contain water for wash-out and refilling pur-

poses, means for supplying clean fresh water to said tank, a blow-off line connected with said tank below the water level therein and adapted to be connected to a locomotive boiler whereby blow-off steam only from a locomotive boiler is conducted to said tank to heat the water therein, thermostatically controlled means for maintaining the water in said tank at a predetermined 5 temperature suitable for wash-out purposes,

means for conducting said water from said tank to the drops in a round house, an independent source of steam supply, and means at the drops whereby steam from said independent source is utilized to further heat 15 said partially heated water to bring the same to a temperature suitable for refilling purposes.

FRANK W. MILLER.
